UNITED STATES PATENT OFFICE.

WILLIAM F. W. HENRY, OF HAMMOND, INDIANA.

WATER-TUBE-FIRE-BOX BOILER.

1,152,021.

Specification of Letters Patent. Patented Aug. 31, 1915.

Application filed December 15, 1914. Serial No. 877,335.

To all whom it may concern:

Be it known that I, WILLIAM F. W. HENRY, a citizen of the United States, residing at Hammond, in the county of Lake, State of Indiana, have invented certain new and useful Improvements in Water-Tube-Fire-Box Boilers; and I do hereby declare the following to be a full, clear, and exact description of the invention, such as will enable others skilled in the art to which it appertains to make and use the same.

This invention relates to certain novel and useful improvements in a water tube fire box boiler adapted especially for heating purposes, or in connection with a heating system employing radiators located at different points throughout the building.

In carrying out my invention it is my purpose to provide a boiler of this type wherein the water in its circulation through the boiler structure will be constantly subjected to the action of the heat so that the water may be quickly and readily heated.

A further object of my invention is the provision of a boiler wherein the fire box is equipped with groups or banks of water tubes located at the sides of the water drum, beneath such water drum and at the rear thereof, the various banks of tubes being connected in the circular system of the boiler so that the efficiency and economy of the latter is greatly increased.

I also propose to provide a boiler wherein the various groups or banks of tubes may be easily, quickly and conveniently cleaned, and wherein, when desired, worn out or damaged tubes may be readily replaced with new tubes.

Another object of the invention is to provide a boiler of this class which will embody the desired features of simplicity, durability, and wherein a maximum heating capacity is attained with a minimum consumption of fuel.

With the above recited objects and others of a similar nature in view, my invention consists in the construction, combination and arrangement of parts set forth in and falling within the appended claims.

In the accompanying drawings: Figure 1 is a view partly in elevation and partly in longitudinal section of a boiler structure embodying my invention, with the arrows indicating the course of the heated gases. Fig. 2 is a view in side elevation of a water tube fire box boiler embodying my invention, the

boiler setting being omitted. Fig. 3 is a vertical sectional view taken on the line 3—3 of Fig. 1 and looking in the direction of the arrows. Fig. 4 is a view in front elevation. Fig. 5 is a detail view partly in elevation and partly in section, taken on the line 5—5 of Fig. 2 and showing the connection of one of the vertical headers or legs with the water drum. Fig. 6 is a vertical sectional view taken on the line 6—6 of Fig. 5. Fig. 7 is a sectional view taken on the line 7—7 of Fig. 1. Fig. 8 is a vertical sectional view taken through a portion of one of the front water legs or headers and showing the connection of one of the water tubes 22 and one of the short tube sections 23.

Before entering into a detailed description of my invention, I will briefly state that it embodies among other features a water drum having the usual horizontally disposed fire tubes extending therethrough. To this water drum I connect four banks or groups of tubes, one bank being located at each side of the furnace, substantially horizontal, one bank being located below the water drum with the tubes of this bank lying between the bars of the grate, as shown in Fig. 7, and one bank being located beneath and at the rear of the drum, this latter bank being inclined upwardly and rearwardly, preferably at an angle of approximately forty-five degrees, and it is, of course, to be understood that all of these banks of tubes are connected together and into the general water circulation system of the boiler. Furthermore, short sections of the tubes or nipples alining with the water tubes, constituting the side and bottom banks, project through the front of the boiler structure so that the water tubes may be readily and quickly cleaned, or even replaced when desired, the short tubes or nipples being removed for these purposes. The tubes are alternate with the lower or bottom bank and lie between the bars of the grate, and this grate which is preferably of the rocker type, may be raised and lowered to decrease or increase the space between the bottom or lower bank of tubes and the grate bars for the purpose of accommodating different grades and sizes of fuel.

Referring now to the accompanying drawings in detail, the letter A indicates the furnace structure as an entirety, of which 1 is the bridge wall, 2 the ash pit, and 3 the front wall. The rear of the structure is provided with the clean out door 4, while the front

of the furnace has the usual ash pit door 6, the fire door 7 and the clean out door 8 located above the fire door. The combustion chamber of the boiler is indicated at C, and 5 in the upper portion of this chamber is located the water drum D, while E indicates the passage for the heated gases and products of combustion leading to and communicating with the rear flue F, connected with 10 the chimney in the usual manner. The water drum D is provided with the usual supply inlet, and from the top of the drum leads a discharge pipe 9 from which branch pipes lead through the building to the various radiators. As these pipes and radiators forming part of the heating system, do not enter into the present case, they need not be described in detail.

The water drum D is provided with the 20 usual bank of horizontally disposed spaced parallel fire tubes indicated at 10, these tubes opening up through the front and rear heads 11 and 12 of the drum respectively. The side walls of the boiler structure A are built to provide the lower longitudinally extending ledges 13, and the upper longitudinally extending, overhanging ledges 14. These side walls are lined with fire brick or other refractory material, as 30 at 15, while the upper portion of the drum D extends through the roof 16 of the combustion chamber, this roof being also made of fire proof brick or other refractory material, and forms the floor of the horizontal 35 section of the passage E.

I will now proceed to describe the water tube construction and arrangement for the fire box. Located at each side of the combustion chamber and adjacent the front of 40 the furnace, is a vertical tubular water leg 17, while located at each side of the combustion chamber and adjacent the rear thereof, is a vertically inclined tubular water leg 18. Each of the front water legs 17 is provided 45 with a series of spaced nipples 19, and a second series of spaced nipples 20, while each of the rear water legs 18 is provided with a single row or series of spaced threaded nipples 21. A bank of spaced, horizontally disposed parallel tubes 22 have their forward ends rolled or expanded in the nipples 20 in the usual manner, while the rear ends of these tubes are threaded and secured into the nipples 21 so that the tubes 50 22 connect the nipples 20 of each front water leg with the nipples 21 of each rear water leg on the same side of the combustion chamber. Threaded into each nipple 19, as shown in Fig. 8 is a relatively short 55 forwardly extending tube 23 which extends through the front wall of the furnace and is closed by a cap 24. The vertical banks of tubes made up of these short tubes 23 are intended to facilitate the cleaning and repairing 60 of the side banks of tubes, as herein-

after explained. The upper and lower ends of the vertical front water legs 17 terminate in T-couplings 25 and 26 respectively, while the upper and lower ends of the rear vertically inclined water legs 18 terminate in 70 similar T-couplings shown at 27 and 28, respectively. Extending horizontally between and connected to the lower T-couplings 26 of the water legs 17 is a header 29 which extends above and across the front 75 of the grate T. A similar horizontally disposed header 30 extends transversely between and is connected to the T-couplings 28 at the lower ends of the rear water legs 18. A bank of horizontally disposed water 80 tubes shown at 31 connects the transverse horizontal header 29 with the transverse horizontal header 30, and it will be seen by reference at Fig. 7 of the drawings, the tubes of this horizontal bank of tubes 31 85 are alternate with and lie between the bars of the grate T. Thus the burning fuel or fire lies directly on this bank of tubes which is thus subjected to internal heat. Depending from the rear portion of the boiler is 90 a single water tube 32 which is connected as at 33 with the transversely disposed horizontal header 34, this header lying preferably directly beneath the drum, and, of course, is elevated a considerable distance 95 above the lower horizontal bank of tubes 31. A bank of tubes 35, inclined at an angle of preferably about forty-five degrees, connects this rear transverse header 34 with the lower header 30. As will be seen the 100 lower header 30 rests upon the shoulder 35 cut in the bridge wall, while this bridge wall is rearwardly inclined or cut away as at 36 to permit the erection of the inclined bank of tubes 35. The tubular dead ends 105 35' are provided for the header 34 and the bank of tubes 35 so that the header may be readily cleaned. These dead ends are closed by caps 37 which may be removed for cleaning and repairing, and access to the rear 110 bank of tubes may be had through the clean out door 4. In order to fasten each of the vertical water legs to the sides of the water drum, I provide a connection between each 115 leg and the drum which, as will be seen by reference to Fig. 5, includes a flanged collar 38 fastened to the side of the boiler, and between which collar and the jam nut 39 is clamped the upper T-coupling or head of the water leg, suitable packing rings 40 being interposed in the connection. Threaded onto the connection thus formed, is a tubular shank 41, the bore of which communicates with the opening 42 in the side of the boiler, and this shank is provided with a head 43 so that the shank may be unscrewed or removed from the joint for the purpose of cleaning. This tubular shank is further provided with a port 44 for the circulation 120 of the water. At the lower end of each wa- 125 130

ter leg is a connection comprising a jam nut 45 between which and the adjacent end of the T-coupling of the leg is a packing ring 46. A tubular shank 47 projects 5 through the wall of the furnace and communicates with the lower header, each of these tubular shanks 47 being adapted to have the ends 48 of the radiator pipes R connected therewith.

- 10 The grate T includes the grate bars t, and a pair of parallel supporting bars 49 arranged above and at opposite sides of the ash pit, these supporting bars being slotted as at 50 for the reception of the rocker bars 15 51. As shown in Fig. 7, the grate bars t are arranged alternately relative to the tubes of the lower bank of tubes 31, and the depending webs 52 of these grate bars. Each rock shaft 51 has one of the grate bars 20 thereon provided with a depending web 53, and these webs are pivoted as at 54 to the operating bar 55, the forward end of which extends through the ash pit door and which is pivotally connected at 56 to the rocking 25 lever 57, the latter being pivoted at its lower end as at 58 to the bracket 59. The rocker grate is adapted to be adjusted to and from the lower horizontal bank of tubes 31 by raising and lowering the rocker bars in their 30 slots, suitable adjusting bolts 60 being provided for maintaining the bars in their adjusted position.

From the above description, taken in connection with the accompanying drawing, the 35 construction and operation of my improved boiler will be apparent to those skilled in the art.

When the boiler is in use, the burning gases issuing from the fire on the grate and 40 lower bank of tubes 31, pass up and around the side banks of tubes, these gases flowing rearward of the combustion chamber to the rear inclined bank of tubes heating the latter, and thence through the rear of the combustion chamber, to and through the tubes 45 10 in the water drum to the front of the furnace, thence upward and rearward through the passage E and out through the flue F, as is indicated by the arrows in Fig. 1. It 50 will be noted that the gases in their transit, not only pass and heat the side bank of tubes, but also pass and heat the rear inclined bank of tubes 35, and also passing through the tubes 10 of the drum, these 55 gases heating the water in the drum. The result is a complete heating of the water carrying sections of the boiler, for it will be seen that the drum and flues therein, as well as the water tubes, water legs and 60 headers all form heating surfaces. The direction followed by the water in its circulation from the drum through the water tubes is shown in Fig. 2, the water flowing through the downtake connection 32 into the header 65 34, thus down the inclined bank of tubes 35

to the lower header 30, thence through the rear inclined water legs 18, to the side banks of tubes 22 to the front water legs and to the boiler, the heated water leaving the boiler through the pipe 9.

It will be noted that I have provided an exceedingly simple, yet efficient and economical form of boiler which may be readily cleaned when desired, and in which a relatively great heating area is provided for 70 the water, the circulating system of the boiler being broken up into banks or groups of water tubes through which the water may pass in such manner as to be subjected directly to the heat from the fire and from 75 the heated gases.

When it is desired to clean the mud, scale and other foreign matter from the side banks of tubes, the caps 24 on the short sections of tubes 23 may be removed, and as 80 these short tubes 23 are of greater cross diameter than the water tubes 24, ready access may be had to the latter with the usual tube cleaner. If it is desired to remove a damaged tube from the side bank of tubes, 85 that is to say to replace one of the tubes 22, the short pipe section 23 opposite the damaged tube is unscrewed and removed, and as the nipple 19 into which this short section 23 is screwed, is considerably larger in cross 90 diameter than the alining pipe, entrance with a chisel or other tool may be had through this nipple to reach the upset or expanded end of the damaged tube. The latter is then cut or broken down and unscrewed at its other end from the rear 95 header. The new tube is now passed through the alining nipples 19 and 20 in the front water leg to the alining nipple on the rear water leg into which the rear end of the 100 pipe is screwed. The usual ferrule is placed around the front end of the tube, and a tube expander is employed to expand the end of the tube in the usual manner to make it water tight with the water leg. The short tube 105 23 is then replaced. Tubes of the bottom bank and of the rear or inclined bank may be cleaned and removed and replaced in substantially the same manner.

While I have herein shown and described 110 my invention as embodying particularly the form of boiler structure adapted especially for hot water heating, it will be evident that it may be readily embodied in the form of a boiler for steam heating purposes, it being only necessary to reduce the height of the bank of tubes in the drum and locate the smoke box at the front end of the boiler instead of at the back end, suitable water gages being set in the drum at proper points 115 to indicate the height of the water.

While I have herein shown and described one particular embodiment of my invention, I wish it to be understood that I do not confine myself to all the precise details of con- 120 125 130

struction herein set forth by way of illustration, as modification and variation may be made without departing from the spirit of the invention or exceeding the scope of 5 the appended claims.

What I claim is:

1. The combination with a furnace including the combustion chamber, a grate and a passage for the products of combustion leading from the combustion chamber to the chimney flue, of a water drum, a bank of fire tubes extending through the water drum, a bank of water tubes located at each side of the combustion chamber and 10 communicating with the water drum, a horizontally disposed bank of tubes located at the grate and communicating with the side banks of tubes, and a rear bank of tubes communicating with the lower bank of tubes 15 and with the water drum.
2. In an apparatus of the class described, the combination with a furnace including the grate, the combustion chamber and the passage for the products of combustion leading 20 to the chimney flue from the combustion chamber, of a water drum, a bank of fire tubes extending through the water drum, vertically disposed front and rear water legs located at the sides of the combustion chamber 25 and connected with the water drum, tubes connecting the front and rear water legs, a front header at the lower ends of the front water legs, a rear header at the lower ends of the rear water legs, a bank of tubes 30 connecting said headers and located at the grate, a rear header located above the header at the lower ends of the rear water legs, an inclined bank of tubes connecting the last two headers, and a connection between said 35 rear header and the drum.
3. In an apparatus of the class described, the combination with a furnace including a grate, the combustion chamber, and the passage for the products of combustion 40 leading from the combustion chamber to the chimney flue of the furnace, of a water drum, fire tubes extending through the water drum and through which the products of combustion pass from the combustion 45 chamber to the passage, a bank of tubes located at each side of the combustion chamber and provided with front headers, and banks of tubes extending from the front 50 headers through the front wall of the furnace.
4. In an apparatus of the class described, the combination with a furnace including a grate, the combustion chamber and the passage for the products of combustion leading 55 from the combustion chamber to the chimney flue of the furnace, of a water drum having fire tubes extending therethrough and through which the products of

combustion pass from the combustion chamber to the passage, a water downtake connected with the drum, a header connected with the downtake, an inclined bank of tubes connected at their upper ends with said header and lying above the bridge wall of the furnace, a second header to which the lower ends of the inclined bank of tubes are connected, a bank of tubes located at each side of the combustion chamber, rearwardly inclined water legs to which the rear ends of the vertical banks of tubes are connected, 75 said water legs being connected to the drum and to the lower header, front vertically disposed water legs to which the front ends of said vertical banks of tubes are connected, the upper ends of said water legs being connected with the drum, a front header to which the lower ends of said front water legs are connected, horizontally disposed tubes lying between the bars of the grate and connected with the front and rear headers, and banks of tubes connected with the front water legs and extending through the front walls of the furnace, and a clean out 80 device for said headers and tubes.

5. The combination with a furnace including the combustion chamber and a grate therefor, of a water drum, a bank of tubes located at each side of the combustion chamber and communicating with the water drum, and a substantially horizontally disposed bank of tubes located at the grate and 90 communicating with the side banks of tubes.

6. The combination with a furnace and a water drum, of a bank of tubes located adjacent the combustion chamber and communicating with said drum, a header for the bank of tubes, and a supplemental bank of tubes connected with the header and extending through passages in the wall of the furnace, said supplemental tubes alining 100 with the tubes of the first mentioned bank of tubes.

7. The combination with a furnace including the combustion chamber and a grate therefor, a water drum, a bank of water tubes located at each side of the combustion chamber and communicating with the water drum, a substantially horizontally disposed bank of tubes located adjacent the grate and below the water drum and communicating 110 with the side banks of tubes, and a bank of tubes communicating with the horizontally disposed bank of tubes and with the water drum.

In testimony whereof, I affix my signature, in the presence of two witnesses.

WILLIAM F. W. HENRY.
